[57] **CLAIM**

The ornamental design for scroll saw, as shown and described.

DESCRIPTION

FIG. 1 is a perspective view of a scroll saw, showing our new design;

FIG. 2 is a left side elevational view thereof;

FIG. 3 is a right side elevational view thereof;

FIG. 4 is a top plan view thereof;

FIG. 5 is a front elevational view thereof;

FIG. 6 is a rear elevational view thereof;

FIG. 7 is a bottom plan view thereof;

The views while shown on a variety of scales for clarity are intended to represent a single design.
